By

Edgar W. Patterson
ATTORNEY.

UNITED STATES PATENT OFFICE.

EDGAR W. PATTERSON, OF LOS ANGELES, CALIFORNIA.

PRESSURE-PACKED PUMP.

Application filed March 21, 1927. Serial No. 177,000.

This invention relates to the oil producing industry and particularly to a novel oil well pump.

The ordinary oil well pump consists of a barrel which is attached to the lower end of a pump tubing and a plunger which is reciprocated in the barrel by means of a string of sucker rods which extends to the surface of the ground through the pump tubing. The plunger is ordinarily in the form of a sleeve fitting tightly in the barrel.

The ordinary forms of oil well pumps are quite efficient when applied to wells which are less than four thousand feet in depth but operate rather unsatisfactorily when used in deeper wells.

It is an object of my invention to provide a pump which is quite efficient when used in any well and which may be efficiently applied to the pumping of very deep wells.

In the standard form of pump it is quite necessary that the plunger fit tightly in the barrel since the full pressure of the oil being lifted is exerted to force liquid downward between the plunger and the barrel.

It is an object of my invention to provide pressure chambers which are so situated as to act as a sealing means to prevent leakage between the piston and the barrel. By using such pressure chambers the initial fit between the plunger and the barrel need not be accurate and as the plunger and barrel wear the efficiency of the pump is not materially affected.

Since it is not necessary for the various parts of the pump to be accurately fitted together, it is possible to use drawn seamless tubing for many of the concentric members, and thus greatly reduce the initial cost, since the standard form of pump now in use consists of members which are ground to fit together with exceedingly small clearance.

Other objects and advantages of the invention will be made evident hereinafter.

Referring to the drawing in which I illustrate my invention,

Fig. 1 is an elevation.

Fig. 2 is a vertical section of the upper end of the invention.

Fig. 3 is a vertical section of the lower end of the invention.

Fig. 4 is a diagrammatic section illustrating the invention in a single view but with the vertical distances or lengths greatly reduced.

Fig. 5 is a section taken on the line 5-5 of Fig. 2.

Fig. 6 is a section taken on the line 6-6 of Fig. 2.

Fig. 7 is a section taken on the line 7-7 of Fig. 2.

Figs. 8, 9, 10 and 11 are sections taken on the respective lines of Fig. 3.

Referring to Fig. 1, the numeral 11 represents a pressure packed pump embodying my invention. This pump is placed at the lower end of a pump tubing 12 which extends to the surface of the ground through an oil string 13. The pump is operated by means of a string of sucker rods 14 which extends through the pump tubing 12 and has the upper end thereof connected to a walking beam 15 which is operated by the common pitman and crank mechanism indicated generally at 16.

The pump 11 has a barrel 30. Secured to the lower end of the barrel 30 is a lower collar 31 having a conical seat 32 adapted to receive a standing valve unit 33. The standing valve unit 33 is of standard form, having a conical seat 34 and a standing valve in the form of a ball 35. Connected to the upper end of the barrel 30 is an upper collar 37, by means of which the barrel may be secured to the lower end of the pump tubing 12. The collar 37 has an internal tapered seat 39 which is adapted to receive a plug or closure 40. Secured to the plug or closure 40 and extending downward into the barrel 30 is a quill 42.

The upper collar 37 is provided with a hole 29 which is drilled therethrough into the conical seat 39. When the plug 40 is seated in the seat 39 the hole 29 is closed, but when the pump mechanism is lifted upward for the purpose of "pulling" the pump for repairs the plug 40 is also lifted, thus opening the hole 29 and allowing the contents of the tubing 12 to drain back into the well even though the standing valve 35 remains seated. It is highly desirable to so drain the tubing before it in turn is lifted from the well as otherwise the fluid carried by each joint is spilled upon the derrick floor as the joint is unscrewed, this being commonly referred to as a "wet job". By draining the tubing I not only prevent a wet job but it is also not necessary to lift the additional weight imposed by the oil in the tubing.

The plunger of the pump comprises a 110

2

plunger tube 43 which extends through the plug 40 and through the quill 42, with considerable clearance therebetween. In a three or four inch pump the annular clearance between the outside of the tube 43 and the inside of the quill 42 and plug 40 may be about one-sixteenth of an inch. The upper end of the plunger tube 43 has a cage 46 secured thereto, this cage being located 10 above the plug 40. The cage 46 is provided with a pin 47, by means of which the plunger may be attached to the string of sucker rods 14. The lower end of the cage 46 is provided with a shoulder 48 which, when 15 the plunger is lowered beyond the lower end of its normal stroke, may engage an upper face of the plug 40 and be used to drive the plug 40 downward tightly into the seat 39. The lower end of the plunger tube 43 has a 20 working valve body 49 secured thereto which carries a seat 50 and a working valve in the form of a ball 51. Secured to the body 49 and extended upward therefrom in the barrel 30 is a plunger sleeve 54. The plunger 25 sleeve 54 fits rather loosely in the barrel 30, there being about 20/1000 of an inch clearance. As shown best in Figs. 3 and 4, an annular space is provided around the plunger tube 43 below the lower end of the quill 42, and this space comprises the lower pressure chamber 55 of the pump. As illustrated in these figures, the upper end of the plunger sleeve 54 is considerably above the lower end of the quill 42 when the plunger of the pump is at the lower end of its stroke, so that the quill 42 fits inside the plunger tube 54 even when the plunger is in its lowest position.

The quill 42 fits loosely inside the plunger sleeve 54, there being initially about one-sixteenth of an inch or more of clearance at this point. Surrounding the quill 42 above the upper end of the plunger sleeve 54 is an upper pressure chamber 56. It will be noted 40 that the volume of both the lower pressure chamber 55 and of the upper pressure chamber 56 is reduced on the up stroke and increased on the down stroke of the pump.

For the purpose of preventing sand from 50 accumulating in the bottom of the lower pressure chamber 55, I provide one or more small holes 58 which are drilled in the plunger tube 43 into the central fluid course 60 extending through the plunger tube 43.

55 The operation of the invention is substantially as follows.

With the parts in the position shown in the drawing the plunger is ready to start on its up stroke. The working valve 51 closes 60 at this time and the oil in the pump and in the pump tubing above the working valve is elevated. The standing valve at this time opens and oil is allowed to flow into the lower end of the barrel between the plunger and the standing valve 35.

At the beginning of the up stroke the oil in both the lower pressure chamber 55 and the upper pressure chamber 56 is at substantially the pressure of the oil in the central fluid course 60. This pressure is of course 70 the static pressure due to the oil in the tubing 13.

As the plunger starts up, the volume of the oil in both the lower pressure chamber 55 and the upper pressure chamber 56 is decreased. This causes oil to be forced from the upper pressure chamber 56 through the clearance between the quill 42 and the plunger sleeve 54 into the lower pressure chamber 55 and from the lower pressure chamber 55 80 upward through the clearance space between the plunger tube 43 and the quill 42 and through the holes 58. Since these clearances are small, some pressure is necessary to cause a flow of oil therethrough and the pressure 85 in the upper pressure chamber 56 is greater than the pressure in the lower pressure chamber 55, which in turn is greater than the pressure in the central fluid course 60. Owing to this higher pressure oil flows from 90 these pressure chambers back into the central fluid course 60.

This condition holds even when the clearance between the plunger sleeve 54 and the barrel 30 increases to a considerable degree. It is of course obvious that as long as the pressure in the pressure chambers 55 and 56 is greater than the pressure in the central fluid course 60, no oil can flow from the central fluid course into these chambers and the pressure chambers act as a seal to prevent leakage past the plunger.

On the down stroke of the pump the volume of the pressure chambers 55 and 56 is increased and the pressure therein falls below the pressure in the central fluid course 60. This lowering of pressure may be sufficiently great to form a partial vacuum in the pressure chambers 55 and 56. On the down stroke the standing valve 35 seats and the working valve 51 lifts, allowing oil to pass upward through the central fluid course 60. 105

When it is desired to lift the plunger to the surface of the ground, this may be done without disturbing the barrel. The plunger 115 is moved upward until the upper end of the plunger sleeve 54 engages the lower end of the plug 40, at which time the plug 40 will be removed from the seat 39, thus clearing the holes 29 and allowing the tubing to drain. The upward movement of the plug 40 opens the upper end of the barrel 30 so that the plunger and the plug and quill may be lifted to the surface of the ground. When the plunger is to be installed again, 120 the parts are lowered, the plug dropping into the seat 39. By lowering the plunger beyond the lower end of its normal stroke the plug may be forced tightly in its seat as previously mentioned. 125

The pump of my invention is found to be quite efficient in practice and it is believed that this efficiency is due to the pressure chambers 55 and 56.

5 I claim as my invention:

1. In a reciprocating pump of the class described, the combination of: a barrel; a standing valve adapted to prevent a downward movement of fluid through an opening 10 at the lower end of said barrel; a plunger fitting tightly in said barrel and forming a pressure-tight joinder therewith; a working valve adapted to prevent a downward movement of fluid through a fluid course formed 15 through said plunger; and walls forming a pressure chamber which decreases in volume on the up stroke of the pump, said chamber being at all times in communication with the space above said working valve through 20 an opening so constricted as to allow pressure in excess of the tubing pressure to be built up in said pressure chamber on the up stroke of the pump.
2. In a reciprocating pump of the class described, the combination of: a barrel; a standing valve adapted to prevent a downward movement of fluid through an opening 25 at the lower end of said barrel; a plunger fitting tightly in said barrel and forming a pressure-tight joinder therewith; a working valve adapted to prevent a downward movement of fluid through a fluid course formed 30 through said plunger; a plunger tube extending upwardly from said plunger; and a 35 walls cooperating with said tube to form a

pressure chamber which decreases in volume on the up stroke of the pump, said chamber being at all times in communication with the space above said working valve through an opening so constricted as to allow pressure 40 in excess of the tubing pressure to be built up in said pressure chamber on the up stroke of the pump.

3. In a reciprocating pump of the class described, the combination of: a barrel; a 45 standing valve adapted to prevent a downward movement of fluid through an opening at the lower end of said barrel; a plunger fitting tightly in said barrel and forming a pressure-tight joinder therewith; a working 50 valve adapted to prevent a downward movement of fluid through a fluid course formed through said plunger; a plunger tube extending upwardly from said plunger; and a quill secured in pressure-tight relationship 55 with the barrel, extending downwardly inside said plunger into the fluid space therein and cooperating with said tube to form a pressure chamber which decreases in volume on the up stroke of the pump, said chamber 60 being at all times in communication with the space above said working valve through an opening so constricted as to allow pressure in excess of the tubing pressure to be built up in said pressure chamber on the 65 up stroke of the pump.

In testimony whereof, I have hereunto set my hand at Los Angeles, California, this 15th day of March, 1927.

EDGAR W. PATTERSON.
